CLAIM

I claim the ornamental design for a motorized disconnect assembly, as shown and described.

DESCRIPTION

FIG. 1 is a perspective view of an ornamental design for a motorized disconnect assembly in the environment of a motorized disconnect system, according to the present disclosure.

FIG. 2 is a front view of the motorized disconnect assembly of FIG. 1.

FIG. 3 is a first side view of the motorized disconnect assembly of FIG. 1.

FIG. 4 is a rear view of the motorized disconnect assembly of FIG. 1; and,

FIG. 5 is a second side view of the motorized disconnect assembly of FIG. 1.

The solid lines in FIGS. 1-5 illustrate a motorized disconnect assembly according to the present disclosure. The broken lines illustrate the environmental structure and form no part of the claimed design.
